UNITED STATES PATENT OFFICE.

LESTER M. SAWIN, OF CHICAGO, ILLINOIS.

MERCHANDISE-DISPLAYING DEVICE.

Application filed September 21, 1927. Serial No. 220,940.

This invention relates to dispensing and display containers of the general type disclosed in my Patent No. 1,451,055, dated April 10, 1923. The patent referred to shows 5 a glass jar or case for holding salted nuts, confectionary or the like. Within the case is an inclined partition for the purpose of keeping the bulk of the contents of the case at the forward side thereof. In the lower 10 portion of the partition is an opening to allow the contents to flow into the space below and rearwardly of the partition. An opening in the rear side of the case below the partition gives the salesperson access to the 15 nuts or other goods which reach said space through the opening in the partition.

The goods are introduced into the case through the upper end thereof, the mouth of the case being normally closed by means of 20 a depressed cover which also serves as a tray to hold small bags or other filled containers.

In practice the cases are set upon a show case or counter. The merchant usually has 25 a number of such display cases, and some attention is required from time to time to keep the cases arranged in an orderly fashion.

One of the objects of the present invention 30 is to provide a tray for displaying filled bags or other containers, which will also serve to hold a number of display cases in orderly arrangement side by side on a show case or other support.

35 A further object is to provide such a tray which will also serve as a closure for the display cases.

When the upper ends of the display cases are of approximately the same over-all dimensions as the lower ends thereof, it is 40 practicable to use a tray embodying the present invention as a seat for a plurality of display cases, and the invention contemplates such employment of the tray at the option 45 of the user.

The invention further contemplates the use of the tray in holding in position display cases stacked one upon another.

In the accompanying drawings, 50 Figure 1 is a front elevation showing two display cases standing upon a tray embodying the features of my invention, a similar tray being positioned upon the upper end of said display cases.

55 Fig. 2 is a view on a smaller scale showing a tier of display cases, the individual

cases being held in position by means of trays embodying the invention.

Fig. 3 is a fragmental vertical sectional view taken in the plane of line 3—3 of Fig. 1. 60

Fig. 4 is a vertical sectional view in the plane of line 4 of Fig. 3.

In the drawings, 1 denotes a glass display case, the body of which is approximately square in horizontal cross-section. The 65 case 1 has a circular mouth 2. Within the case is a partition 3 which may be of sheet metal or other suitable material, said partition extending from a point on the rear wall of the case downwardly and forwardly to 70 the bottom of the case. In the lower portion of the partition 3 is an opening 4 through which the nuts or other merchandise may flow until the angle of repose is reached. In order that the interior of the 75 display case may be conveniently cleaned, the partition 3 is made removable, being simply set in place within the case. The mouth 2 of the case is made large enough to permit the introduction and withdrawal of the partition. 80

In the rear wall of the case 1 is an opening 5 which is normally closed by means of a hinged door 6. When the door 6 is opened the contents of the space below the partition 3 may be scooped out. 85

A tray embodying the present invention may be made of sufficient length for use with two or more display cases. As herein shown, the tray A comprises a rectangular bottom 90 B adapted to rest upon the mouth of two display cases 1, a rim C extending upwardly around the perimeter of the bottom B, and a flange D extending downwardly around the perimeter of said body. It will be seen 95 that the flange D fits about the mouths of the display cases and thus prevents horizontal displacement of the tray in any direction. To prevent vertical displacement of the tray, there is provided upon a portion of 100 the flange, say, the forward portion thereof, a horizontal locking flange E extending inwardly into position to underlie a circular overhanging external shoulder 7 encircling the upper end or mouth of each case. It will 105 be seen that by tilting the rear portion of the tray A upwardly until the rear portion of the flange D is above the horizontal plane of the display case, the tray may be pushed forwardly until the flange E is out from 110 under the overhanging shoulder 7, whereupon the tray may be lifted off the display.

cases; but a person attempting to remove the tray by lifting the forward portion thereof will be unable to do so.

In the construction herein shown, the tray 5 A is formed of sheet metal, but any other preferred material may be employed.

As indicated in the drawings, the tray A may, if desired, serve as a seat for a plurality of display cases, the width and length 10 of the space bounded by the rim C being approximately a multiple of the dimensions of the lower end of a display case 1, so as to receive a plurality of display cases and hold them in orderly position side by side.

15 As shown in Fig. 2, a plurality of trays A may be used in holding in position a plurality of display cases stacked upon one another.

It will be evident that the tray herein 20 shown serves to keep a plurality of display cases neatly lined up on a show case or counter with the delivery openings 5 properly positioned toward the rear of the counter.

The tray A is of inexpensive construction 25 and takes the place of a plurality of separate trays or closures, thus effecting a saving in manufacture.

While I have shown the flange D as extending continuously around the tray, it will 30 be understood that it need not be continuous or uninterrupted so long as it comprises portions lying at all four sides of the series of display cases.

I claim as my invention:

35 1. A set of display cases comprising a plurality of display cases placed side by side, a tray set upon the upper ends of said display cases, said tray comprising a portion extending downwardly about the upper ends of the 40 display cases to hold the latter against horizontal displacement, said tray further com-

prising an upwardly extending rim, a like number of similar display cases set upon said tray, said rim serving to hold the lower portions of the last mentioned display cases 45 against horizontal displacement, and a similar tray set upon the upper ends of the last mentioned display cases, the last mentioned tray serving to hold the upper ends of the last mentioned display cases against horizontal displacement and also serving as a tray for merchandise.

2. A set of display cases comprising a plurality of display cases located side by side, each case having a delivery opening in its 55 rear wall, a tray located upon the upper ends of said display cases, said tray comprising a flange extending downwardly about the upper ends of the display cases to hold the latter against horizontal displacement, said 60 tray further comprising an upwardly extending rim, an inwardly extending locking part on the forward longitudinal portion of said flange, and an overhanging shoulder on the forward upper portion of the cases beneath which said locking part extends.

3. The combination of a plurality of display cases located side by side, each case having a mouth at its upper end, and a combination tray and closure for said mouths 70 comprising a bottom covering said mouths, an upstanding rim surrounding the bottom, a downwardly extending flange surrounding the mouths of the cases, and a member on a portion of said downwardly extending 75 flange, said member extending inwardly into position to underlie a portion of one of said cases to prevent upward displacement of the side of the tray which has said member.

In testimony whereof, I have hereunto 80 affixed my signature.

LESTER M. SAWIN.
